United States Patent Office

Des. 224,455
Patented July 25, 1972

224,455

PEN DESK SET

Gerald N. Oberton, Addison, Ill., assignor to
Sanford Research Company

Filed Jan. 18, 1971, Ser. No. 107,609

Term of patent 14 years

Int. Cl. D19—06

U.S. Cl. D74—5

FIG. 1 is a side perspective of a pen desk set showing my new design;

FIG. 2 is an enlarged rear elevation thereof;

FIG. 3 is a top plan view;

FIG. 4 is a front elevation thereof;

FIG. 5 is a side perspective of another embodiment thereof wherein only one pen and pen well are employed; and

FIG. 6 is a side elevation of the side opposite to FIG. 5.

I claim:

The ornamental design for a pen desk set, as shown and described.
